UNITED STATES PATENT OFFICE.

JOHN F. COURSON, OF PITCAIRN, PENNSYLVANIA.

DRAFT-GEARING FOR RAILWAY-CARS.

No. 873,843.

Specification of Letters Patent.

Patented Dec. 17, 1907.

Application filed March 7, 1907. Serial No. 361,027.

To all whom it may concern:

Be it known that I, JOHN F. COURSON, a citizen of the United States, residing at Pitcairn, Pennsylvania, have invented certain new and useful Improvements in Draft-Gear for Railway-Cars, of which the following is a specification.

My invention relates to draw gear apparatus for railway cars and my object is to provide a simple and convenient construction and arrangement of parts which will accomplish the ends in view.

The invention consists in the features, combination and arrangement of the parts hereinafter described and particularly pointed out in the claims.

In the accompanying drawings, Figure 1 is a vertical sectional view through the apparatus parts being shown in side elevation. Fig. 2 is a transverse sectional view. Fig. 3 is a view similar to Fig. 1 with the parts in a different position. Fig. 4 is a detail sectional view of one of the friction blocks. Fig. 5 is a front view of the same. Fig. 6 is a sectional view of the other friction block which is a companion to that shown in Fig. 4. Fig. 7 is a front view of Fig. 6. Figs. 8 and 9 are views of the wedge bar.

In these drawings 1 indicates the coupling bar, 2 the strap or yoke bolted thereto at its ends and which yoke embraces within it the improved arrangement and combination of parts constituting my invention. This improvement includes a wedge bar 3 tapered at its opposite ends on its upper and lower faces, the said tapered ends entering tapered openings in the friction blocks 4-5. A pair of these blocks is arranged at each end of the wedge bar and the outermost member of each pair of friction blocks is arranged to bear upon an abutment plate 6, 6'. These abutment or follower plates extend transversely of the draft gear and at their ends they bear upon abutments 7 bolted or riveted as at 8, to the sills 9 of the car. The friction blocks have inclined faces 10 in contact and have limiting stops 11 at the ends of these inclined faces which limit the lateral motion of one block in respect to the other. A spring 12 is interposed between the pairs of friction blocks, said spring surrounding the wedge bar 3.

The arrangement of the wedge bar in respect to the friction blocks and the arrangement of the friction blocks to each other is

such that the upper inclined face of the wedge bar bears upon the incline of the tapered opening in one of the friction blocks or plates, while the lower inclined face of the wedge bar at the same end of said bar bears against the inclined wall of the tapered opening in the companion friction block; so that upon a relative movement of the wedge bar and friction blocks in the line of draft the said friction blocks or plates will be moved in opposite directions by reason of the wedge shaped end of the wedge bar working in the conical openings or recesses of the friction blocks or plates. This action takes place under both a pulling or buffing strain and is illustrated in Fig. 3, wherein the friction blocks are shown as having been moved inwardly in relation to the yoke and in this movement friction has been created under heavy pressure between the inclined faces of the companion friction blocks. As represented in Fig. 3. The spring 12 has been compressed, owing to the draft gear having been subjected to the buffing action. In this action the abutment plate forms the stop or backing piece and the spring is compressed and the parts of the draft gear operated by the movement of the front abutment or follower plate 6' towards the rear abutment plate 6, the latter abutment plate remaining in position because it bears upon the abutment 7. As before stated the friction blocks are provided with shoulders or limiting stops at 11 which are of importance as they limit the separating movement of the friction blocks and keep the blocks in proper position and from moving or pushing farther back than necessary. These stops also keep the friction blocks from pressing unduly against the yoke and they perform, therefore, an important office in preventing shock or jar on the yoke. When the spring reacts such shock would otherwise tend to bend the yoke or make the rivets work loose.

I claim as my invention:

1. In combination in a draft gear, a spring, a pair of friction blocks at the end of the spring and movable one upon the other transversely of the line of draft and wedge means for moving both of the said friction blocks transversely, substantially as described.

2. In combination in a draft gear, a spring, a pair of friction blocks at each end of the said spring under pressure thereof and mov-

- able on each other transversely of the line of draft and wedge means for moving the said friction blocks transversely when the gear is subjected to buffing or pulling strain, substantially as described.
3. In combination in a draft gear, a spring, a pair of friction blocks arranged to move transversely of the line of draft having inclined surfaces in contact and having also inclined surfaces to coöperate with wedge means and wedge means for operating the said friction plates or blocks, substantially as described.
4. In combination in a draft gear, a spring, a pair of friction blocks or plates arranged at the end of the spring having tapered openings or recesses and a wedge member coacting therewith, substantially as described.
5. In combination in a draft gear, a spring, pairs of friction blocks or plates between which the said spring is interposed, a member within the spring and having tapered ends for operating the members of the pairs of friction blocks and abutment means, said friction blocks operating transversely one on the other and in opposite directions, substantially as described.
6. In combination in a draft gear, a spring, a pair of friction blocks having inclined surfaces in contact and movable transversely of the line of draft, wedge means for operating the said friction blocks and stop means for limiting the outward movement of the said friction blocks, substantially as described.
7. In combination in a draft gear, a spring, friction blocks movable transversely to the line of draft and having inclined surfaces in contact and inclined wedge receiving surfaces, wedge means for operating the said friction blocks, a yoke surrounding the spring, friction blocks and wedge means and stops on the friction blocks to limit their outward movement and prevent shock, substantially as described.
8. In combination in a draft gear, a spring, pairs of friction blocks between which the spring is interposed said friction blocks having inclined wedge receiving surfaces and being movable transversely to the line of draft, a bar within the spring having inclined ends engaging the inclined wedge receiving surfaces of the friction plates or blocks, a yoke or draft frame and abutment means, substantially as described.
9. In combination in a draft gear, a spring, a pair of friction plates or blocks at each end of the spring movable transversely to the line of draft having inclined surfaces in contact, and openings or recessed at their central portions presenting inclined surfaces, a member loosely arranged in the spring and having inclined or wedge shaped ends and a draft frame and abutment means, substantially as described.
10. In combination in a draft gear, a spring, a pair of friction blocks at each end of the spring movable transversely to the line of draft, the members of each pair having their friction surfaces in contact to move one upon the other, and wedge means for moving the members of each pair inwardly from their normal positions under buffing or pulling strains, substantially as described.
11. In combination in a draft gear, a spring, a pair of friction blocks, one of said blocks having an opening extending therethrough and wedge means extending through the said opening and contacting with the wall thereof and having its projecting end contacting with the other wedge block, said wedge means serving to move the friction blocks one upon the other transversely of the line of draft, substantially as described.
12. In combination in a draft gear, a spring, a wedge member, a friction block having a friction surface and a coacting friction portion, an abutment and follower means, said wedge block moving inwardly when acted upon by the wedge member and having its friction surface pressed with increased force upon its co-acting friction surface when it is moved inwardly, substantially as described.
13. In combination in a draft gear, a spring, a wedge member, a wedge block having an inclined surface, a co-acting member having an inclined friction surface and follower and abutment means, said wedge block moving transversely and inwardly under buffing and pulling strain and also having movement longitudinally of the draft gear to augment the compressing action on the spring, substantially as described.
14. In combination in a draft gear, a spring, a wedge member, a pair of friction blocks, having inclined friction surfaces, co-acting friction members having inclined friction surfaces and abutment and follower means, said friction blocks having movement inwardly and transversely under buffing and pulling strains and having also movement towards each other to augment the compressing action of the spring under buffing and pulling, substantially as described.
15. In combination in a draft gear, a spring, friction members, and abutment and follower means, said friction members under buffing and pulling strains having movement to augment the compressing action of the spring, substantially as described.
16. In combination in a draft gear, a wedge bar, a pair of friction blocks at each end thereof having inclined friction surfaces in contact, a spring encircling the wedge bar and abutment and follower means, the members of each pair of friction blocks having movement inwardly or away from the sills under buffing and pulling strains and the opposing members of the pairs of friction blocks having movement towards each other to aug-

ment the compressing action on the spring under buffing and pulling strains, substantially as described.

17. In combination in a draft gear, a
5 wedge bar, a pair of friction blocks at each
end thereof having inclined surfaces in con-
tact, a spring interposed between the pairs of
friction blocks and abutment and follower
means, the members of each pair of friction
10 blocks moving inwardly in opposite direc-

tions and having a clamping effect on the
wedge bar at each end, substantially as de-
scribed.

In testimony whereof, I affix my signature
in presence of two witnesses.

JOHN F. COURSON.
